UNITED STATES PATENT OFFICE.

EDWARD P. WAGGONER, OF SYRACUSE, NEW YORK, ASSIGNOR TO A. A. GRIFFING IRON COMPANY, OF JERSEY CITY, NEW JERSEY.

DESIGN FOR A CASING FOR GENERATORS.

SPECIFICATION forming part of Design No. 34,109, dated February 19, 1901.

Application filed January 2, 1897. Serial No. 617,851. Term of patent 14 years.

To all whom it may concern:

Be it known that I, EDWARD P. WAGGONER, of Syracuse, in the county of Onondaga, in the State of New York, have invented and produced a new and useful Design for a Casing for a Generator, of which the following is a specification, reference being had to the accompanying drawings, showing a part thereof.

Figure 1 is a perspective view showing the front face and one of the sides of a casing for a generator embodying my design. Fig. 2 is a similar view illustrating the rear face and said side of the casing, and Fig. 3 is a side elevation of said casing.

The leading and essential features of my design consist of the top A, formed substantially rectangular in shape and having the upper portions of its upright faces extended or curved toward each other, the substantially rectangular body B, having the corners of its upright faces curved in cross-section and the upper portions of said faces extended or curved toward each other and united to the lower portions of the upright faces of the top A, and the base C, formed substantially rectangular in cross-section and having its upright faces flared outwardly toward their lower edges and formed with longitudinally fluted or corrugated corners.

The top A is substantially rectangular in shape and is distinguished from the body B by being formed of less width and length than the upper face of said body. The upper portions a of the upright faces of the top A are extended or curved toward each other, and the lower portions a' of said faces are flared outwardly from each other.

The body B is substantially rectangular, and the corners b of its upright faces are curved in cross-section. The upper portions 4c of said faces of the body B are extended or curved toward each other and are united to the lower portions a' of the corresponding faces of the top A. The opposite side faces of the body B are formed with figured ornamentation b' b', and the front and rear faces of said body are provided with projecting or raised panels b² b³ b⁴ of substantially rectangular form, the panels b² b³ of the front face being arranged one above the other. 50

The base C is formed substantially rectangular in cross-section and is provided with an ornamented border c at its lower edge. The upright faces of the base C are formed with figured ornamentation c' and flare outwardly 55 toward the border c. The corners of the base C are fluted or corrugated longitudinally and also flare outwardly toward the border c.

A casing for a generator embodying my design presents a characteristic and pleasing 60 appearance.

What I claim is—

The design for a casing for a generator, substantially as shown and described.

In testimony whereof I have hereunto 65 signed my name, in the presence of two attesting witnesses, at Jersey City, in the county of Hudson, in the State of New Jersey, this 24th day of December, 1896.

EDWARD P. WAGGONER.

Witnesses:

J. M. C. THOMAS,
JOHN GALT CRAIG.
